UNITED STATES PATENT OFFICE.

AMOS L. SWAN, OF CHERRY VALLEY, NEW YORK.

IMPROVEMENT IN DOOR-BELLS.

Specification forming part of Letters Patent No. **158,446**, dated January 5, 1875; application filed April 11, 1874.

To all whom it may concern:

Be it known that I, AMOS L. SWAN, of Cherry Valley, in the county of Otsego and State of New York, have invented a new and valuable Improvement in Door-Bells; and I do hereby declare that the following is a full, clear, and exact description of the construction and operation of the same, reference being had to the annexed drawings, making a part of this specification, and to the letters and figures of reference marked thereon.

Figure 1 of the drawing is a representation of a plan view of my bell, and Fig. 2 is a sectional view of the same. Fig. 3 is an outside view of my bell.

This invention has relation to improvements in house and signal gong bells; and it consists, first, in the cam and swinging sector, pivoted together and arranged in connection with the hammer-lever, a pivoted connecting-arm, and a stop-pin, whereby the desired motion is given to the hammer; second, in the construction and novel arrangement of the pivoted key, connecting-arm, and cam, whereby a double or single action of the hammer may be secured at option.

In the accompanying drawings, the letter A indicates a sector-shaped lever, which is pivoted to the under side of the base-plate B, which is recessed underneath to receive the sector and the remaining parts of the operating mechanism, presently to be described. The plate B is provided with a circumscribing flange, b, bounding the recess a, which is perforated at c for the passage of the pull-wire d, and is provided with lugs e extending outward from its edge, for the passage of suitable fastening-screws. A post, C, extends upward from the upper side of the bed-plate for the attachment of the bell D. The sector-lever A is slotted at f upon a curve having its center at the pivot g of said lever, said slot playing about a stop, h, which is fixed to the bed-plate and extends through the slot. To one horn, k, of the sector is attached the pull-wire d, and to the other, k', one end of an actuating-spring, a', which is secured to the bed-plate. The play of the sector is determined by a stop, b'. To the free end of the sector at z, on the opposite side of the slot from the pivot g, and at the middle of the curve, is pivoted the cam

E, one end of which is recessed or notched at c', to provide two horns, d' and d'', for engagement with the stop h. The other end of the cam is pivoted at z' to a connecting-arm, F, which is, in turn, pivoted at z'' to the crank e' of the hammer G, the shank of which is journaled at f' by passing it through a perforation through the bed-plate. A spring, g', engages with a horn, h', at the crank end of the arm F, and serves to keep this arm pressed toward the cam E, the operation of the spring being limited by a stop, l, secured to the bed-plate, and engaging with the crank e', when a double action of the hammer is required. H indicates a key-stop, pivoted to the bed-plate at the side of the arm F.

When a single stroke only is desired, this key is turned toward the arm, thereby preventing the cam from moving the full length of the return stroke, and thus keeping the hammer from the bell on this return stroke.

On the upper side of the bed-plate is secured an arm, K, to which is attached a bumper, L, of rubber or other elastic material, to receive the back stroke of the hammer, thereby instantly overcoming its momentum, and communicating force thereto in the direction of the bell.

This is of great importance in gongs of large size, where the hammer is of considerable weight. With this improvement, the momentum or strength of stroke of the hammer against the bell is directly proportioned to the rapidity of the pull upon the bell-wire, which is not the case when the reacting device is not employed.

By means of the raised and flanged bed-plate, the entire action is concealed and kept free from dust, without danger of accidental disarrangement, and the bell can be attached to a finished door or jamb or wall without marring the same by recessing or mortising to receive the action.

It will be observed that the stop h and the pivots g and z'' are arranged in line across the bed-plate B. The pivots z and z' are transversely movable, with reference to this line, when the pull-wire is actuated, the first moving with the sector, and the last being thrown, by the engagement of the stop h with the horns d' and d'', first in the direction of the

pull, and then in the reverse direction, the spring g' at the same time operating the hammer-crank.

What I claim as new, and desire to secure by Letters Patent, is—

1. The combination, with the slotted sector-lever A, and the horned cam E pivoted thereto, of the fixed stop h, connecting said sector-lever and cam, substantially as specified.

2. The combination, with the sector-lever A and horned cam E, pivoted together, of the

fixed stop h, hammer-crank e', spring g' , connection F, and stop H, adjustable for single or double strokes, substantially as specified.

In testimony that I claim the above I have hereunto subscribed my name in the presence of two witnesses.

AMOS L. SWAN.
